UNITED STATES PATENT OFFICE.

STIVIN POULOS, OF BOSTON, MASSACHUSETTS.

ALARM.

Application filed May 8, 1926. Serial No. 107,719.

This invention relates to alarms and more specifically to fire alarms.

The object of this invention is to produce a fire alarm system whereby an alarm will be sounded simultaneously in each room when a fire is discovered in any one room.

The chief novelty lies in the use of a soft, malleable metal hook which passes around the clapper in the alarm and holds the same silent.

Still other novelty lies in the means employed for always keeping the alarm line taut.

Further novelty will be shown in the drawings and specification.

In the drawings like numerals designate similar parts.

In the drawings, Figure 1 is a diagrammatic view showing the signal system installed in a number of compartments.

Figure 2 is a side elevation of the installed system in one compartment.

Figure 3 is a perspective of the signal showing the hook holding the alarm inoperative with the springs which are at the end of the system on each floor.

Referring to the drawings, numeral 1 designates a cord to which is attached at both ends, a spring 2. In line with the cord 1 is an alarm 3 with a clapper member 4. Opposite the clapper member 4 attached to the cord 1 is a soft, malleable hook 5 capable of engaging clapper member 4. Where the cord passes through a partition, tubes 6 are used, and where the cord 1 makes a turn, pulleys 7 are used. Eyelets 8 carry the cord 1 along the walls.

As the alarm actually operates, when a fire breaks out in any one room, the flames will ignite the cord 1 and sever same, and since the cord 1 is under tension, the hook 5, which is formed of soft, malleable metal, will straighten out and release the clapper 4 in every compartment thus giving a warning to any occupants who may be in the compartments. In case there are occupants of the compartment where the fire breaks out and the flames have not reached such intensity as to ignite the cord 1, the occupant who discovers the fire may either sever the cord 1 or pull the same and thus release the soft, malleable hooks 5 from around the clappers 4 in each compartment. By using a hook 5 of the described material, there is no danger of the hook 5 falling back into place and re-engaging the clapper

member 4 as might be the case if a flexible material or a different device were used.

Having described my invention what I claim as new is:

1. A mechanically operated signal having a sound producing member, a soft malleable retaining member mounted on a cord, said retaining member normally engaging said sound producing member to retain same inactive, and operable means for releasing said retaining member. 60

2. A mechanically operated signal having a sound producing member, a soft malleable hook mounted on a cord, said hook normally engaging said sound producing member to retain same inactive, spring operable means for straightening said hook and thereby releasing said sound producing member. 70

3. A mechanically operated signal, having a sound producing member, a soft non-flexible malleable hook mounted on a cord, said hook normally engaging said sound producing member to retain same inactive, and operable means for straightening said hook thereby releasing said sound producing member. 75

4. A mechanically operated signal having a sound producing member, a soft non-flexible, malleable hook mounted on a cord, said hook normally engaging said sound producing member to retain same inactive, spring operable means for straightening said hook and thereby forming means for releasing said sound producing member. 80

5. A mechanically operated signal having a sound producing member, a soft malleable hook normally engaging a sound producing member to retain same inactive, an inflammable cord under tension, said inflammable cord having the soft, malleable hook attached thereto and capable of straightening said hook when the cord ignites. 85

6. A mechanically operated signal system for a building having a plurality of compartments, a sound producing member in every compartment, a soft malleable hook mounted on an inflammable cord, said hook normally engaging the sound producing member to retain same inactive, and operable means for pulling said hook to straighten the same, and thereby release said sound producing member in every compartment. 100

7. A mechanically operated signal system for a building having a plurality of compartments, a sound producing member in every compartment, a soft malleable hook

mounted on an inflammable cord, said hook normally engaging the sound producing member to retain same inactive, and operable spring means for pulling said hook to straighten the same, and thereby release said sound producing member in every compartment.

8. A mechanically operated signal system for a building having a plurality of compartments, a sound producing member in every compartment, a soft non-flexible malleable hook mounted on an inflammable cord, said hook normally engaging the sound producing member to retain same inactive, and operable means for pulling said hook to straighten the same, and thereby release said

sound producing member in every compartment.

9. A mechanically operated signal system for a building having a plurality of compartments, a sound producing member in every compartment, a soft non-flexible malleable hook mounted on an inflammable cord, said hook normally engaging the sound producing member to retain same inactive, and operable spring means for pulling said hook to straighten the same, and thereby release said sound producing member in every compartment. 20 25

In testimony whereof I affix my signature.

STIVIN POULOS.
